UNITED STATES PATENT OFFICE.

EARL C. BOOTH, OF INDIANAPOLIS, INDIANA, ASSIGNOR TO INDIANAPOLIS PUMP & TUBE COMPANY, OF INDIANAPOLIS, INDIANA, A CORPORATION.

PROCESS AND APPARATUS FOR MAKING STENCILS.

Application filed November 3, 1927. Serial No. 230,716.

This invention relates to a new and novel process and apparatus used therewith for producing stencils, such as are employed for stencilling names on toys, packing boxes and 5 the like.

The principal object of the invention is to quickly and cheaply produce a stencil which will have the advantages of the more expensive type of stencils now in use. This has reference to that type of stencil wherein there is employed a frame over which is secured a mesh, such as silk or organdie protected by suitable coating, such as celluloid or the like, leaving open meshwork through which the paint or coloring may be forced by a squeegee for leaving the desired imprint. This type of stencil has been more commonly made by securing celluloid over the frame which has been cut to leave open spaces for the lettering or other design, and covering such open spaces with a silk or organdie which is firmly stretched and held in place by suitable adhesive or binder.

The feature of this invention resides in the simple process and apparatus used in connection therewith for quickly and cheaply producing a stencil of the above character by merely tacking the organdie to the frame and providing a plurality of metal letters 30 or designs which may be repeatedly used, and magnetically securing the same in position over the mesh. After the metal letters are properly positioned and magnetically held in place, a suitable filler is brushed over the fabric so as to fill and close the interstices thereof excepting where the metal letters are positioned. The metal letters may then be magnetically released and removed, leaving open spaces forming the stencil. Thus 40 the metal letters may be used over again in varying combinations.

The full nature of the invention will be understood from the accompanying drawings and the following description and claims:

In the drawings, Figure 1 is a plan view of the stencil. Fig. 2 is a section taken on the line 2-2 of Fig. 1. Fig. 3 is a perspective view of the magnet with the stencil mounted thereon. Fig. 4 is a central vertical section through the magnet with the stencil frame and lettering mounted thereon.

In the drawings there is illustrated an apparatus used in the process of making stencils, as well as the stencil made thereby.

Fig. 1 is illustrative of the stencil having a rectangular wooden frame 10 surrounding a suitable space which is adapted to be filled with the paint or coloring used and to receive a squeegee for forcing it through the 60 openings in the fabric 11 in the usual manner. As illustrated herein, there are openings 12 in the fabric forming the letters of the desired name. By "openings" is meant the open mesh of the fabric, the remaining portion 65 thereof being closed by a suitable filler.

For producing the above desired stencil, there is provided a magnetic block 13 having an upper face of suitable dimensions to receive the frame 10 thereover, whereby said 70 frame will enclose the same. The block 13 and the upper face thereof is divided into three sections, a central section 14 running longitudinally thereof, and two side sections 15 and 16 positioned on each side of the central section. Each of said sections is formed of suitable metal and separated by the lead sheets 17 positioned between the same. The block 13 is mounted upon a base 18 in which there is a magnetic coil 19. The side sections, which comprise metal blocks, are supported upon the upper surface of the base 18 in electrical contact therewith, but insulated from the coil 19 by lead strips 20. The coil 19 is further insulated from the base 18 85 by the lead strips 21. The intermediate section 15 comprises a metal block which extends down into the base 18 within the coil 19.

By means of this arrangement a suitable electro magnet is formed by the coil 19 surrounding the block 14, which when energized causes magnetic lines of force to pass upwardly through the top surface of the block 14 and down through the side blocks 15 and 16 through the base 18 and back through the bottom surface of the block 13. When the frame 10, having a suitable silk or organdie fabric stretched over the bottom thereof, is inverted and mounted over the top of the magnet 13, said fabric rests directly upon the upper surfaces of the three blocks 14, 15 and 16. Suitable metal plates in the form of letters or designs 21 are thereupon mounted in the desired position on the mesh so that they span the central block 14 and extend 95 onto the blocks 15 and 16. The current is then turned on to energize the coil 19 and set up the magnetic lines of force which will thereupon pass through said magnetic blocks and metal plates 21 lying on the face thereof. 100 105 110

This force will anchor the plates firmly in position on the face of the blocks by reason of the magnetic force being exerted on the ends thereof which extend over a portion of the side blocks 15 and 16. While the plates are thus held firmly in place, the operator applies a suitable filler over the fabric so as to completely fill and close the interstices thereof other than where the metal plates are placed. Upon the partial drying of the filler, or while the same is still plastic, the coil is de-energized and the plates removed by any suitable means, such as a horseshoe magnet or the like. Upon the filler becoming completely dry, the stencil is then ready for use.

In commercial practice, after the various letters of the alphabet have been cut from the metal or the design to be stencilled has been cut, the stencil may be rapidly made since it is only necessary to tack organdie or similar fabric over the frame, place the same on the magnet, arrange the letters thereon and apply the filler. The stencil is then completed excepting for the removal of the metallic letters or designs. It will be noted that the application of the filler will seal the rough edges of the fabric where it is tacked to the

frame, so that no great care need be taken in this respect.

The invention claimed is:

1. The process of making stencils consisting in providing a frame, securing a mesh thereon, magnetically securing a metallic plate thereto for producing the desired lettering or design, applying a filler to the mesh, and thereafter removing the metal plate therefrom.

2. The process of making a stencil, consisting in securing a metallic plate for forming the lettering or design upon a mesh by magnetic force, applying a filler to the mesh over said plate, and thereafter removing the same.

3. The process of making a stencil consisting in providing a frame having a mesh secured thereto, positioning a metallic plate thereon to form the desired design, placing the same in a magnetic field for securing said metal plate to position, applying a filler to said mesh about said plate, and thereafter removing said mesh from said magnetic plate and said plate from the mesh.

In witness whereof, I have hereunto affixed my signature.

EARL C. BOOTH.
